UNITED STATES PATENT OFFICE.

CHRISTIAN M. ENGEBRETSON, OF STARBUCK, MINNESOTA.

COMBINED MUSIC STAND AND CASE.

1,203,864.

Specification of Letters Patent.

Patented Nov. 7, 1916.

Application filed March 8, 1915. Serial No. 13,065.

To all whom it may concern:

Be it known that I, CHRISTIAN M. ENGEBRETSON, a citizen of the United States, residing at Starbuck, in the county of Pope, 5 State of Minnesota, have invented certain new and useful Improvements in Combined Music Stands and Cases; and I do hereby declare the following to be a full, clear, and exact description of the invention, such as 10 will enable others skilled in the art to which it appertains to make and use the same.

This invention relates to a combined music stand and case.

The primary object of the invention resides in the provision of a device which when extended will form a music stand and which when folded constitute an exceedingly neat and compact case in which the movable parts of the stand will be located.

20 With this and other objects in view, such as will appear as the description progresses, my invention comprises the combination and arrangement of parts as set forth in and falling within the scope of the appended 25 claims.

Referring to the drawing: Figure 1 is an elevational view of my device when the parts thereof are extended for use as a music stand. Fig. 2 is a similar view showing the parts 30 folded. Fig. 3 is a longitudinal sectional view, showing the position of the several parts when they are in such position as shown in Fig. 1. Fig. 4 is a similar view when the parts bear the relationship shown 35 in Fig. 2. Fig. 5 is a fragmental detail of the desk. Fig. 6 is a fragmental detail showing the manner of mounting the desk in the inner tube. Fig. 7 is a fragmental detail showing the manner of mounting the legs.

40 Fig. 8 is a bottom plan view when the legs are extended. Fig. 9 is a similar view of the locking plate removed. Fig. 10 is a vertical sectional view of the desk. Fig. 11 is a horizontal sectional view on line 11—11 of Fig. 4. 45 Fig. 12 is an elevational detail, showing the music desk started to its folded position.

Referring to the drawing wherein like parts are indicated by like characters throughout the several views:—In the embodiment of my invention shown, I have dis-

closed a desk indicated generally by the reference letter A and a standard indicated by the reference letter B. This standard consists of a tubular casing 15 which forms the upper end of the standard and a second tubular member 16. These members are hinged together, as at 17, and are maintained in alinement by means of a spring 18 which is mounted on the member 15 and engages a lug 19 on the member 16. In order that this 55 standard may be maintained in a vertical position, I have provided a plurality of legs 20 which are secured to a sliding plug 21 in the member 16 and extend outwardly through radial slots 22 in the tubular member 16. 60 This plug 21 is normally pressed outwardly by a coil spring 23 which is secured thereto and to the upper end of the member 16. In order that the legs 20 may be locked in their 65 extended positions, I have rotatably mounted on the bottom of the member 16 a locking plate 24 which has a plurality of radially extending slots 25 therein which have off-set portions 26. When the legs extend outwardly from the member 16 they are locked 70 in the off-set portions 26 of the slots 25 in the locking plate 24 so that they are prevented from moving inwardly into the member 16 as will be obvious.

In order that the plug 21 together with 80 the legs 20 may be maintained in the member 16 against the tension of the spring 23, at the will of the operator, I have provided a locking pawl 27 which engages a shoulder 28 on the plug 21 and prevents the same 85 moving outwardly. The pawl 27 is held in released position by means of a ring 30' rotatably mounted on the tube 16 and having an offset portion 27'. When the pawl 27 has one end disposed in the offset portion 27' 90 said pawl is in locking position as clearly shown in Figs. 4 and 11. In releasing the pawl same is manually manipulated to the flexed position shown in Fig. 3 and the ring 30' rotated to dispose the offset portion 27' 95 out of line with the pawl 27 when the latter will be held in released position.

Mounted within the member 15 of the standard B is a tubular member 28' in which is slidably mounted a socket member 100

29. It will be noted that the members 15 and 28' are held in various adjustments by friction. This socket member is normally pressed outwardly by a coil spring 30 in 5 the member 28', but is limited in its outward movement by a pin 31 sliding in a slot 32. Pivotally mounted within the socket member 29 on the pin 31 is an upwardly extending arm 34 which has on the lower end 10 thereof flanges 35 through which the pin 33 extends. When the arm 34 is in such position that it extends outwardly from the standard B it is held in a position inclined from the vertical by a spring 36 which en- 15 circles the pin 31, is secured to the arm 34 and bears against the socket member 29. Slidably mounted on this arm 34 is a strip 37 which is guided by means of members 38 having lugs 39 extending through a slot 40 20 in the strip 37. Pivotally secured adjacent the upper and lower ends of the arm 34 are arms 41 which extend outwardly in opposite directions and are secured together at their outer ends by bars 42 which are piv- 25 otally secured thereto. Pivotally secured to the extreme upper end of the strip 37 are brace bars 43 which are in turn pivoted, as at 44, to the lower arms 41 between their ends. The construction which I have just de- 30 scribed forms the music desk A. In operation when it is desired to push the desk A within the member 15 of the standard B the strip 37 is pulled upwardly against the tension of a spring 44' secured to the lower 35 arms 41 and tending to hold the desk open, at which time the arms 41 and the bars 42 and 43 will be simultaneously moved into substantial alignment with the arm 34. The folded desk is then pushed downwardly 40 against the tension of the spring 32. In order that the desk may be maintained within the member 32, I have provided on the upper end of one of the bars 43 a projection 45 which when located within the 45 member 32 is engaged by a latch member 46 which is locked in position by a clip 47. Thus it will be seen that both the desk and legs may be folded, the desk pushed into the member 32 which is locked in the 50 member 15 of the standard B and the legs into the member 16 of the standard B. After the operation of pushing these members into their respective casings has been accomplished the spring 18 may be disengaged from the pin 19 and the members 15 and 16 of the standard B swung about the hinge 17 as a pivot so as to lie substantially parallel. In order that the ends of these members 15 and 16 may be covered, I have 55 pivoted to the lower ends of the members 15 and 16 caps 48 and 49 on each of which is a spring clip 50. When the members 15 and 16 lie parallel in their folded position the cap 48 is swung so as to cover the adj- 60 65 cent ends of the said members and is main-

tained in such position by the engagement of the clip 50 thereon with the pin 19 on the member 16, while the cap 49 is swung over the adjacent ends of the said members 15 and 16 and maintained in such position by the engagement of the clip 50 with a pin 51 on the member 28', which pin is provided for the purpose. Secured to the member 15 is a suitable handle 53 by means of which the device may be carried when folded.

From the foregoing description it will be seen that I have provided a device which comprises such parts that it may be unfolded and will then constitute a complete 80 music stand, but which when folded will constitute an exceedingly neat package wherein the movable parts such as the legs and the desk are located within two casings which form the standard of the device. I 35 have so constructed the device that the legs and desk will be automatically projected from the standard in which they are located upon the release of the locking means by the operator.

While I have illustrated and described a particular embodiment of my invention, I have merely done so for the sake of convenience and I do not wish to be limited to that particular embodiment as it is obvious 95 that numerous changes may be made within the details of construction thereof without in any way departing from the spirit of the invention or exceeding the scope of the appended claims.

What I claim is:—

1. In a music stand and case, a standard consisting of a pair of aligned tubular members, a desk carried by one of the members, a block slidably mounted in the other member, legs carried by the block and adapted to extend through the lower end of the last mentioned member, a spring for forcing the block toward the lower end of the member, a locking plate rotatably mounted on the lower end of the tubular member adjacent the legs, the said plate having a plurality of radially extending slots through which the legs extend and offset portions in the slots, the said plate being arranged by its rotation on the lower end of the standard to maintain the legs in their extended positions when the legs are located in the offset portions of the slots.

2. In a music stand, the combination with 120 a tubular member, of a socket member slidably mounted therein, an arm carried by the socket member, a strip slidably mounted on the arm, pairs of arms pivotally mounted on the first mentioned arm, bars pivotally 125 connecting the ends of the corresponding members of the pairs, resilient means for normally maintaining the pairs of arms in angular relation to the first mentioned arm, brace bars pivotally connected to the lower- 130

most pair of arms and to the upper end of the strip, an abutment on one of the brace members and a latch member carried by said socket member for engaging the abutment to maintain the first mentioned arm and the elements carried thereby within the tubular member.

In testimony whereof, I affix my signature, in the presence of two witnesses.

CHRISTIAN M. ENGEBRETSON.
